DRESSER WITH BAMBOO POSTS

Joseph E. Adkinson, 3807 Leland St.,
Chevy Chase, Md. 20015

Filed Feb. 4, 1972, Ser. No. 223,825

Term of patent 14 years

Int. Cl. D6—04

U.S. Cl. D6—154

FIG.1

FIG. 1 is a view in front elevation of the dresser with bamboo posts showing my design.

FIG. 2 is a view in side elevation of the dresser of FIG. 1.

FIG. 3 is a view in top plan of the dresser of FIG. 1. The back of the dresser is conventionally flat and the side not shown is identical to the side shown in FIG. 2.

I claim:

The ornamental design for a dresser with bamboo posts, or the like substantially as shown and described.
